Inventor:
CHARLES L. CLYMER,
Son Andrew B. Ramick,
His Attorney.

Patented Oct. 6, 1925.

UNITED STATES PATENT OFFICE.

CHARLES L. CLYMER, OF ST. LOUIS, MISSOURI, has invented a new and useful Improvement in CAN-LOADING MACHINES, the specification for which was filed May 23, 1921, Serial No. 471,790.

To all whom it may concern: I, CHARLES L. CLYMER, a citizen of the United States, and residing at St. Louis, Missouri, have invented the new and useful Improvement in CAN-LOADING MACHINES, of which the following is a specification.

This invention relates to loading machines, and more particularly to machines for loading cans into boxes or crates for shipment.

One of the objects of this invention is to provide a machine which may be used in connection with such machines as can filling and sealing machines to take the cans delivered by such machines and place them in a box or crate in which they are to be packed for shipment.

Another object of this invention is to provide such a device which shall be capable of loading a packing receptacle in which the cans are arranged in successive layers.

Further objects will appear from the detail description taken in connection with the accompanying drawings, in which:

Figure 1 is a view in elevation of a machine embodying this invention;

Figure 2 is a plan view of one of the carrier arms;

Figure 3 is a section on line 3-3, Figure 2;

Figure 4 is a section on line 4-4, Figure 3 showing the device for locking the can gripping fingers in locked position;

Figure 5 is a view similar to Figure 4, but showing the device in unlocked position;

Figure 6 is a plan view of one of the holders shown in Figure 3;

Figure 7 is an enlarged section on line 7-7, Figure 6; and

Figure 8 is a section on line 8-8, Figure 1.

Referring to the accompanying drawings, 1 designates a platform, conveyor or other device by means of which or on which the cans are delivered from the filling, sealing or similar machine with which this device is to be used. 2 designates a platform or other device upon which the packed boxes or crates are received from the loading machine. This device operates to receive the cans from the table 1 and load them into the packing receptacles which are then delivered to the table 2.

In the device illustrated a frame is provided comprising a base 3 in the form of a ring having mounted thereon a series of

legs 4 supporting a spider 5. The spider 5 has mounted thereon a column 6 adapted to support a shaft 7 having bearings in the spider 5 and the upper end of the column 6 and carrying a four-arm carrier 8. The carrier 8 is thereby mounted for rotation with the shaft 7. The carrier 8 carries at the end of each arm a series of depending can holders 9 adapted to grip and hold a series of cans as will be hereinafter described.

Mounted for vertical reciprocating movement in the spider 5 and a guide bearing 10 mounted on the column 6 is a vertical shaft 11 carrying at its upper end a receiving table 12, which is adapted to receive the cans from the delivering table 1. The lower end of the shaft 11 is equipped with a roller 13 adapted to engage a circular cam 14, mounted as will be hereinafter described, and adapted to raise and lower the table 12.

Another shaft 15 is mounted to slide in the spider 5 and carries a table 16 adapted to receive the box or crate to be loaded and adapted to be engaged at its inner edge by a guide-way 17 to guide it in its vertical reciprocating movement. A pair of cams 18 and 19 are arranged to cooperate with a roller 20 on the lower end of the shaft 15 and are moved as will hereinafter be described so as to raise and lower the table 16.

The end 21 of each arm of the carrier 8 carries a plate 22 on which the holders 9 are mounted, each arm in this case carrying six holders. Each holder comprises a vertically depending tube 25 attached to the plate 22 and carries at its lower end a head 23 supported by a series of straps 24 upon the tube 25. The head 23 is provided with a series of upstanding ribs 26 to which are pivoted at 27 a series of gripping fingers 28. These fingers are provided on one side of the pivot 27 with a downwardly extending portion 29 adapted to engage and grip the outside of a can and provided with a friction lining 30 for that purpose. These fingers are further provided on the other side of the pivot 27 with an extension 31 having a beveled surface adapted to engage the corresponding surface of an abutment 32 mounted on an operating rod 33 passing upwardly through the body of the tube 25 as shown in Figure 3. The abutment 32 rests on the upper surface of the head 23 and has mounted thereon by means of a screw 34 a contact plate 35 adapted to contact with the

head of the can. A washer 36 surrounds the rod 33 and rests upon the tops of the extensions 31 of the fingers 28. A spring 37 surrounds the rod 33 bearing at its lower end against the washer 36 and at its upper end against a retaining member 38 carried by the tube 25. The pressure of this spring on the extensions 31 serves to normally maintain the fingers 28 in open or extended position so that the head of a can may readily be inserted therebetween. It will be obvious from this construction that when the head of a can is brought forcibly into contact with the plate 35, said plate and with it the rod 33 will be lifted against the tension of the spring 37. By this action the abutment 32 will raise the extensions 31 which will cause the fingers 28 pivoting at 27 to force the arms 29 together so as to grip the can as is illustrated in Figure 3.

Mounted on the upper side of the arm ends 21 are a series of rods 39 adapted to slide in bearings 40 and in close proximity to the rods 33. Each rod 39 is provided with a series of locking pieces 41 each adapted to engage a notch 42 in one of the rods 33. The notches 42 are located so as to be in alignment with the locking pieces 41 when the rods 33 are in raised position with the elements 29 gripping the cans. A spring 43 mounted in a barrel 44 on the arm 21 and engaging a collar 45 on a cross head 46 connecting the rods 39 is adapted to normally hold the rods 39 in locking position. The movement of the cross head 46 under the action of the spring 43 is limited by an abutment 47 mounted on the end of a tripping member 48 adapted to slide vertically in a bearing 49 mounted on the carrier 8. A spring 50 bearing at its upper end against the carrier 8 and at its lower end against a pin 51 in the tripping member 48 serves to normally hold said member in depressed position. The abutment 47 is provided with an inclined surface 52 arranged to engage upon upward movement of the member 48 a roller 53 on the cross head 46 so as thereby to move said cross head to the left, Figures 2 and 3, thereby carrying the rods 39 to the left to unlock the rods 33. Upon being thus unlocked the rods 33 will, under the action of the spring 37, move downwardly to open the fingers 29 and release the cans.

Mounted in bearings in the base 3 and in a bracket 54 depending from the spider 55 is a vertical shaft 55 adapted to be driven at a suitable speed by means of a worm gear 56 and a motor or by other suitable means. Fixed to the shaft 55 is a spider which carries the cams 14, 18 and 19 so that when the shaft 55 is driven, the cams will rotate therewith. The shaft 55 also carries at the upper end thereof a pair of arms 58 adapted to intermittently drive the shaft 7 as will presently be described.

A dog 59 is mounted for vertical sliding movement in the end of each arm 58 and carries at its lower end a roller 60 adapted to engage a cam 61 carried by the bracket 54. The dogs 59, of which there are two, are adapted to engage a series of four-arms 62 carried at the lower end and fixed to the shaft 7. The shaft 55 rotates in a counter-clockwise direction as seen from above in Figure 1. The dogs 59, upon arriving in the position shown in Figure 1 have their rollers 60 riding in an elevated portion of the cam 61 and will, therefore, engage the bars 62 so as to carry said bars with them in their rotation. The bars 62 will thus be carried through one-quarter of a revolution when the rollers 60 will engage a sudden decline 63 in the cam 61, being thereby withdrawn from engagement with the bars 62 so as to release said bars. When this position is reached, one of the bars 62 will be located so as to engage a latching device 64 mounted on the spider 59. The device 64 is adapted to arrest the movement of the shaft 7 so as to position the holders 9 for proper engagement with the cans on the table 12. After leaving this position, the dogs 59 will engage a gradually rising portion of the cam 61 which will raise them to a position for reengagement with the arms 62 after another one-quarter of a revolution of the shaft 55. It will thus be seen that the shaft 55 makes one-quarter of a revolution while the shaft 7 remains stationary. Upon the arms 58 again arriving in position for the dogs 59 to engage the arms 62, a tripping member 65 on one of the arms 58 will engage a releasing arm 66 on the latch 64 so as to release said latch in time to permit the arms 62 to move with the arms 58 through the next one-quarter revolution and this cycle will continue to be repeated.

The cams 14, 18 and 19 rotate with the shaft 55. The cam 14 has a raised portion at each of two diametrically opposite points so that the table 12 will be raised twice during each revolution of the shaft 55 and since this shaft moves at double the speed of the shaft 7, the table 12 will be raised each time one of the arms of the carrier 8 is in a position to place a series of holders 9 thereover.

The cam 18 is adapted to raise the table to such a height as to receive a series of cans from the holders 9, said cans being deposited on the bottom of the box or crate carried by the table 16 as soon as the upstanding rod carried by the table 16 contacts with and operates the tripping member 48. After passing this position the cam 18 will lower the table 16 during the subsequent one-quarter revolution of the carrier 8. Said revolution of the carrier will position a new set of holders 9 with their cans over the table 16 after which the cam

19 will again raise the table 16 at this time to a less height than before, so that a new series of cans may be received in a new layer on top of the first layer. The tripping members 48 of each alternate set of holders 9 extend to a lower level than the member 48 so that the upper layer of cans may be properly released by this movement of the table 16.

10 The operation of the device will be readily understood from the foregoing description. The cans being brought to the device upon the table or conveyor 1 are moved on to the table 12 which may be provided with 15 a stop 68 to arrest the cans being moved thereon. After receiving the charge of cans the table 12 is raised by the cam 14 so as to bring the can heads forcibly into engagement with the plates 35 thereby raising 20 the rods 33 to close the gripping fingers 29. Upon such closure the notches 42 will be brought opposite the latches 41 which will be moved by the spring 43 into engagement therewith to lock the fingers in 25 closed position. After this the cam 14 will lower the table 12 so as to disengage the same from the cans held in the holders 9. The moving arms 58 will now carry the dogs 59 into engagement with the arms 62. 30 At the same time the tripping member 65 by engaging the arm 66 will release the latch 64 and the shaft 7 will be carried through one-quarter revolution with the shaft 55. At the end of one-quarter revolution, the 35 roller 60 engaging the incline 63 in the cam 63 will withdraw the dogs 59 from engagement with the arms 62 and the latch 64 will arrest the movement of said arms. This will place a new set of holders 9 over 40 the table 12. The cam 14 will now again raise the table 12 which has in the meantime received a new charge of cans so as to deliver said cans to the holders 9.

45 When this operation has been repeated twice, the first batch of cans will have been carried to a position over the table 16 upon which a box or crate has been placed. At the same time that the table 12 is raised to receive a new batch of cans, the cam 18 50 raises the table 16 and by tripping the member 48 releases the cans which are deposited in the box or crate. The table 16 is then lowered while the holders 9 are moving through the succeeding one-quarter revolution. 55 Upon arrival of the next batch of cans over the table 16, said table will again be raised by the cam 19 at this time to a less height and the operation of the tripping member 48 will deposit a second 60 layer of cans in the box after which the table 16 will again be lowered. The loaded box or crate is now removed to the table 2 and a new empty box placed on the table 16 after which the process is repeated.

65 It will be seen that this invention accom-

plishes its objects. The cans are taken from the receiving table 12 moved to a delivery point and deposited in the box on the table 16. The holders are adapted to positively grip and hold the cans and are locked 70 in holding position. The cans are delivered in batches and successive batches may be delivered one upon the other in successive layers.

75 It is obvious that various changes may be made in details of construction without departing from the spirit of this invention; it is, therefore, to be understood that this invention is not to be limited to the specific details shown and described.

80 Having thus described the invention, what is claimed is:

1. In a can loading device, a series of holders each adapted upon engagement therewith to grasp and hold an article, means for locking said holders, a carrier for said holders adapted to move the same to delivery position, and means for releasing the articles.

85 2. In a can loading device, means adapted upon engagement therewith to grasp and hold a plurality of articles, means for moving said holding means from receiving to delivering position, a movable receiving table adapted to move the articles into engagement with said holding means, a movable delivery table adapted to receive the articles delivered from said holding means, means for delivering the articles, and means 90 for moving said receiving and said delivery tables.

95 3. In a can loading device, means adapted upon engagement therewith to grasp and hold a plurality of articles, means for moving said holding means from receiving to delivering position, a movable receiving table adapted to move the articles into engagement with said holding means, a movable delivery table adapted to receive the articles delivered from said holding means, 100 means for delivering the articles, and means for moving said receiving and said delivery tables in timed relation with said holding means.

11 4. In a can loading device, means adapted upon engagement therewith to grasp and hold a plurality of articles, means for moving said holding means from receiving to delivering position, a reciprocating receiving table adapted to move the articles into engagement with said holding means, a reciprocating delivery table adapted to receive the articles delivered from said holding means, means for delivering the articles, and means for moving said receiving and said delivery tables.

12 5. In a can loading device, means adapted upon engagement therewith to grasp and hold a plurality of articles, means for moving said holding means from receiving to

- delivering position, a movable receiving table adapted to move the articles into engagement with said holding means, a movable delivery table adapted to receive the articles delivered from said holding means, means for delivering the articles adapted to deliver the same in layers, and means for moving said receiving and said delivery tables.
10. 6. In a can loading device, means adapted to grasp and hold a plurality of the articles, means for moving said holding means to delivery position, and means operable at the delivery position adapted to deliver the articles in layers.
7. In a can loading device, means adapted to grasp and hold a plurality of the articles, means for moving said holding means to delivery position, and means operable at the delivery position adapted to deliver one layer of articles upon another.
8. In a can loading device, means adapted to grasp and hold a plurality of the articles, means for moving said holding means to delivery position, and means operable at the delivery position and cooperating with said holding means adapted to deliver the articles in layers.
9. In a can loading device, means adapted to grasp and hold a plurality of the articles, means for moving said holding means to de-

livery position, and means at the delivery position adapted for movement to different positions to receive successive layers of delivered articles.

10. In a can loading device, means adapted to grasp and hold a plurality of the articles, means for moving said holding means to delivery position, and means at the delivery position adapted to cooperate with said holding means to deliver the articles in successive layers.

11. In a can loading device, means adapted to grasp and hold a plurality of the articles, means for moving said holding means to delivery position, and receiving means at the delivery position adapted for cooperation with said holding means to effect delivery of the articles in successive layers.

12. In a can loading device, means adapted to grasp and hold a plurality of the articles, means for moving said holding means to delivery position, and receiving means at the delivery position operating in timed relation with said moving means and adapted for cooperation with said holding means to effect delivery of the articles in successive layers.

In testimony whereof I affix my signature this 13th day of May, 1921.

CHARLES L. CLYMER.
